UNITED STATES PATENT OFFICE.

MANUEL JOSEPH SIQUEIRA, OF BROOKLYN, CALIFORNIA.

BRAKE-BLOCK.

SPECIFICATION forming part of Letters Patent No. 277,360, dated May 8, 1883.

Application filed March 20, 1883. (No model.)

To all whom it may concern:

Be it known that I, MANUEL JOSEPH SIQUEIRA, a citizen of the United States, residing at Brooklyn, in the county of Alameda and 5 State of California, have invented a new and useful Improvement in Brake-Blocks, of which the following is a specification.

My invention relates to that class of brake-blocks used in connection with wagon-wheels, 10 to act by friction on the tire of the wheel and to serve as a wearing-piece interposed between the brake-lever and the wheel. To this end it consists in the construction and combination of parts forming a brake-block, hereinafter 15 described and claimed, reference being had to the accompanying drawings, in which—

Figure 1 is an elevation of the side of the 20 brake-block next the wagon. Fig. 2 is an elevation of the outside, and Fig. 3 is a front view of the same.

A represents the body of the brake-block, consisting of a piece of wood bored through at a, to receive the end of the brake-lever and to rock thereon. This block is provided with 25 a hook, B, pointed to one side, on which hook one end of one or more strips of leather, b, is secured. The leather is drawn lengthwise over the block A, and at its other end is secured by means of a hinged pin, C, like an inverted bosom-pin, passing through a hole in the leather and fastened down by its own hook, as shown. The body-piece of the pin C is firmly secured to the block. D is another similar pin secured to the inner side of the block by a 30 hinge, d, and serving as a lever by which to force the stretched leather into the cross-notch or hollow in the face of the block A. When pressed nearly down the pin or lever D is held

at its outer end and closed into place by another lever, E, similarly hinged to the block 40 at e, and in its turn held down by a hook, F. The hollow in block A beneath pin C is for the treble purpose of keeping the center of the shoe away from the wheel when not in use, of furnishing two bearings — one on each side of 45 said hollow—on the wheel-tire, to prevent the brake from chattering, and of allowing the holding-pin C a resting-place below the line of wear of the wheel and shoe.

By means of this device an old leather may 50 be removed and a new one substituted in a few minutes, and that without injuring the block, whereas it was formerly the practice to nail on the leathers one over another, so that the block frequently became filled with nails 55 and split in pieces. As the leathers are for the purpose of taking the wear, and as they may be replaced when worn, there is no reason why my brake-block should not last as long as the wagon. 60

What I claim as my invention, and wish to secure by Letters Patent, is—

1. The block A, provided with the sidewise-pointed hook B, and the pin C, hinged to said block, in combination with the leather b, with 65 holes in its ends, and adapted to receive the hook B and the pin C, as shown and described.

2. The combination, with the block A, hollowed in its face, the hook B, the pin C, and the leather b, of the hinged lever or pin D, the 70 hinged lever E, and the hook F, as and for the purpose specified.

MANUEL JOSEPH SIQUEIRA.
